UNITED STATES PATENT OFFICE

98,994

DESIGN FOR A CARTON OPENER

Levi Billhimer, New Madison, Ohio

Application August 8, 1935, Serial No. 58,022

Term of patent 7 years

To all whom it may concern:

Be it known that I, Levi Billhimer, a citizen of the United States, residing at New Madison, in the county of Darke and State of Ohio, have invented a new, original, and ornamental Design for a Carton Opener, of which the following is a specification, reference being had to the accompanying drawing, forming part thereof.

I claim:—

The ornamental design for a carton opener, as shown.

LEVI BILLHIMER.
